Assistant Examiner — Cleso Moore, Jr.

(57) **CLAIM**

The inventors claim the ornamental design for the reusable shelf divider, as shown and described.

DESCRIPTION

FIG. 1 is a perspective view of the preferred design;
FIG. 2 is a right side elevational view thereof;
FIG. 3 is a left side elevational view, which is a mirror image of FIG. 2 thereof;
FIG. 4 is a sectional view of the reusable shelf divider I-Beam along '4-4';
FIG. 5 is a right side elevational view thereof;
FIG. 6 is an enlarged view of an encircled portion shown in FIG. 5;
FIG. 7 is an enlarged view of an encircled portion shown in FIG. 5;
FIG. 8 is a top plan view thereof;
FIG. 9 is a bottom plan view thereof;
FIG. 10 is an enlarged view of an encircled portion shown in FIG. 9;
FIG. 11 is an enlarged view of an encircled portion shown in FIG. 9;
FIG. 12 is an enlarged perspective rear view aligned for insertion on the shelf with receptacle in position; and,
FIG. 13 is an enlarged perspective rear view of the reusable shelf divider as installed;
FIG. 14 is a perspective view of the reusable shelf divider as installed on a shelf;
FIG. 15 is an enlarged view of an encircled portion shown in FIG. 14;
FIG. 16 is right side elevational view of the reusable shelf divider in an alternate design;
FIG. 17 is an enlarged view of an encircled portion shown in FIG. 16;
FIG. 18 is an enlarged view of an encircled portion shown in FIG. 16;
FIG. 19 is an enlarged bottom plan front view thereof;
FIG. 20 is an enlarged bottom plan rear view thereof;
FIG. 21 is an enlarged perspective rear view aligned for insertion on the shelf with receptacle in position; and,
FIG. 22 is an enlarged perspective rear view of the reusable shelf divider as installed.

The broken lines shown illustrate environmental structure and form no part of the claimed design.
